(57) **CLAIM**

The ornamental design for a mat for fruits and vegetables, as shown and described.

DESCRIPTION

FIG. 1 is a front perspective view of a mat for fruits and vegetables showing my new design.

FIG. 2 is a front view thereof.

FIG. 3 is a right side view thereof.

FIG. 4 is a left side view thereof.

FIG. 5 is a top plan view thereof.

FIG. 6 is a bottom plan view thereof; and,

FIG. 7 is a rear view thereof.

The broken lines are for illustrative purposes only and form no part of the claimed design.
